UNITED STATES PATENT OFFICE.

HERMAN REINECKE, OF BROOKLYN, NEW YORK, ASSIGNOR OF ONE-HALF
TO GEORGE MERRITT, OF SAME PLACE.

TRAVELING CLOCK.

SPECIFICATION forming part of Letters Patent No. 234,612, dated November 16, 1880.

Application filed May 8, 1880. (Model.)

To all whom it may concern:

Be it known that I, HERMAN REINECKE, of Brooklyn, in the county of Kings, and in the State of New York, have invented certain new and useful Improvements in Traveling Clocks; and I do hereby declare that the following is a full, clear, and exact description thereof, reference being had to the accompanying drawings, making a part of this specification, in 5 which—

Figure 1 is a perspective view of my improved train, the front plate being broken away to give a view of the parts beneath the platform. Fig. 2 is an elevation of the same 15 from the rear, the rear plate being removed, and Fig. 3 is an elevation from one side.

Letters of like name and kind refer to like parts in each of the figures.

My invention belongs to a class of clocks in 20 which the balance-wheel and escapement are arranged to move in a horizontal plane; and it consists in a clock in which the connection between the main train and the platform-train is made at a point between the center wheel 25 and the wheel next in rear of the escape-wheel, substantially as and for the purpose hereinafter specified.

In the annexed drawings, A and B represent the front and back plates of my movement, 30 connected together at suitable points by means of pillars C, in the usual manner.

Journalized within and between the plates A and B is a spring-wheel, D, second-wheel E, center wheel F, and a contrate-wheel, G, which 35 wheels are arranged from below upward in the order named, and each meshes with and imparts motion to a pinion, e, f, or g, upon the staff of the next higher wheel of the train.

The contrate-wheel G meshes with a pinion, 40 h, that is secured upon a vertical staff, h', which staff is journalized within suitable bearings upon or attached to a horizontal platform, I, that is attached to and extends across the upper ends of the plates A and B. Upon the 45 staff h, above the pinion h', is secured a wheel, H, which meshes with the pinion k of an es-

cape-wheel, K, the latter, the escapement, and the balance being pivoted upon the platform I beneath a suitable bridge, L.

While the connection between the main 50 train and the horizontal train is, preferably, made at the pinion h' of the wheel H, such connection may be made, if desired, at any point near the spring-wheel D, but not with the pinion k of the escape-wheel K.

By reason of this construction less delicacy 55 is required in depthing the teeth of the contrate-wheel and the pinion that it meshes with, as the teeth of said wheel and pinion increase in size as they recede in position from the escapement, and variations in depthing are of 60 less consequence, and friction resulting from such variations is more easily overcome.

In addition to the advantages named I am 65 enabled to employ much smaller wheels having firm teeth between the contrate-wheel and the escapement than upon the other side of said contrate-wheel, in consequence of which there is less momentum and inertia to overcome in stopping and starting the escape-wheel 70 than would otherwise be the case.

While the arrangement of the horizontal train upon the upper side of the platform is 75 preferably employed, said train may be wholly or in part arranged above or below said platform, or it may, in part, be placed upon a second lower platform.

Having thus fully set forth the nature and 80 merits of my invention, what I claim as new is—

A clock in which the connection between the main train and the platform-train is made at a point between the center wheel and the wheel next in rear of the escape-wheel, substantially as and for the purpose specified. 85

In testimony that I claim the foregoing I have hereunto set my hand this 10th day of April, 1880.

H. REINECKE.
